UNITED STATES PATENT OFFICE.

GUSTAV KROKER, OF OHLIGS, GERMANY.

COMBINED NAPKIN RING AND HOLDER.

SPECIFICATION forming part of Letters Patent No. 605,487, dated June 14, 1898.

Application filed February 5, 1898. Serial No. 669,230. (No model.)

To all whom it may concern:

Be it known that I, GUSTAV KROKER, a citizen of Germany, and a resident of Ohligs, Prussia, Germany, have invented certain new 5 and useful Improvements in a Combined Napkin Ring and Holder, of which the following is a specification.

This invention relates to an improved napkin-ring which can be readily converted into 10 a clasp or holder for fastening the napkin to the clothes.

In the accompanying drawings, Figure 1 is 15 a side elevation of one form of my improved napkin-ring; Fig. 2, a plan thereof; Fig. 3, a plan of one-half of the ring, showing it converted into a clasp; Fig. 4, a side elevation of the ring, showing it in the state of being parted; Fig. 5, a plan of the parts *c d*, showing them open; Fig. 6, a plan of a modification; Fig. 7, a plan of Fig. 6, showing it converted into a clasp; Fig. 8, a plan of a further modification; Fig. 9, a plan of Fig. 8, showing it converted into a clasp; and Fig. 10, a plan of a still further modification.

25 The napkin-holder is composed of four sections *a b c d*, of which the parts or jaws *a b* are connected by a hinge, and the jaws *c d* are connected by a second hinge, as shown. Hooks at the ends of the jaws are made to 30 interlock, so that the two hinged sections may be connected by being slid one into the other, Fig. 4, to form a complete closed napkin-ring, Fig. 2.

The parts *a c* are provided with rearwardly- 35 projecting noses *e*, adapted to be received by corresponding notches in the adjoining parts. When the ring is opened, each of its duplex sections *a b* or *c d* may be folded to form a 40 clasp or napkin-holder, Fig. 3, which is held in its closed position by spring *f*, secured to

the notched jaw and bearing upon the nose *e* of the adjoining jaw. In this position the clasp may be used for attaching the napkin to the collar, coat, waistcoat, &c.

In Figs. 6 and 7 the sections *a' b' c' d'* are 45 joined by three hinges and one hook-joint, so that the ring can be opened at one point only and forms a duplex clasp. In this modification two springs *f'* are employed in conjunction with the single spring *f''* for engaging 50 nose *e'* and pressing the inner ends of the jaws together, Fig. 7.

In Figs. 8 and 9 the springs *f''* are arranged on the inside of the jaws *a'' b'' c'' d''*, while spring *f''*, engaging nose *e''*, is arranged on the 55 outside to form a square ring or a flat clasp.

In Fig. 10 four hinge-joints are shown, so that the jaws *a''' b''' c''' d'''*, having noses *e'''* and springs *f'''*, are permanently connected and can be manipulated to assume either a round 60 or elongated form.

What I claim is—

1. A napkin-ring composed of a number of 65 jointed sections, rearwardly-extending noses on some of the sections, and springs adapted to engage said noses and secured to the adjoining sections, substantially as specified.

2. A napkin-ring composed of a number of sections connected by hinges and by hook-shaped slip-joints, noses on some of the sections, and springs on the adjoining sections that are adapted to engage said noses, substantially as specified.

Signed by me at Dusseldorf, Germany, this 19th day of January, A. D. 1898.

GUSTAV KROKER.
